UNITED STATES PATENT OFFICE.

ZANA R. LUCAS AND GUY E. CARPENTER, OF WEST CHICAGO, ILLINOIS; SAID
CARPENTER ASSIGNOR TO SAID LUCAS.

MANICURING BUFFER.

Application filed May 20, 1926. Serial No. 110,402.

The invention relates to a manicuring buffer, and particularly to a form of buffer and polisher which is cylindrical, and which is provided in its interior with means to preserve the cylindrical character of the buffer.

One of the principal objects of the invention is to provide a spring means or core in the interior of the buffer which, while maintaining the cylindrical character of the buffer, and supporting the filler and cover in proper operative position, will provide the buffer with resiliency and elasticity, thus assisting in the operation of cleaning, polishing and finishing the finger nails.

15 An object of the invention is also to construct the interior spring means, comprising a cylindrical tube, or tubes, in such a manner that an internal recess or cavity will be formed and will provide an internal variable air cushion with the assistance of the filler and covering of the buffer.

Another object of the invention is to provide in the interior of the buffer, and surrounding the tube, or tubes, a layer, or 25 layers, of kapok, which is a silky down investing the seeds of *Ceiba pentandra*, a species of silk-cotton tree of the Tropics, which is botanically related to the cotton plants, or other soft or downy material.

30 It is a further object of the invention to cover the kapok, or other filler, which in turn covers the interior spring mechanism, with an outer layer of chamois and kid to clean and polish the finger nails, respectively.

35 Another of the objects of the invention is to provide the chamois and the kid covering with extensions beyond the principal outline of the buffer, so that these extensions may be utilized not only for concealing the 40 roughness, creases and folds at the ends of the chamois and kid, but also furnishes and supplies artistic and decorative features, which may be used to simulate flowers, or other objects, and which may be painted or 45 colored to suit the wish of the user.

A further and important object of the invention is to provide a construction which is soft, resilient, and elastic, and which in use will reach every part of the surface of the 50 finger nails, having no hard substance or material to come in contact with, or strike against the fingers, or finger nails.

An additional important object of the invention is to construct the buffer in a cylindrical form so that it may be readily and

naturally grasped and held in the hand of the user, and easily and efficiently operated at any angle to clean and polish the finger nails.

Furthermore, the manicuring buffer of the 60 invention is readily and inexpensively made, may be easily assembled, and may be cleaned to always present an attractive appearance.

The invention will be explained and more 65 clearly understood when read in conjunction with the accompanying drawings, which illustrate embodiments of which the invention is susceptible, it being obvious that changes and modifications may be made without departing from the spirit of the invention, as expressed in the appended claims 70 forming a part hereof.

In the drawings:

Figure 1 is an elevational view of the manicuring buffer showing, in dotted lines, 75 the interior spring tubes with the slit cut therein on the bias and longitudinally of one of the tubes.

Figure 2 is a central, longitudinal, sectional view of the manicuring buffer on the 80 line 2—2 of Figure 3.

Figure 3 is a cross sectional view of the buffer on the line 3—3 of Figure 1, and,

Figure 4 is a view similar to that shown in Figure 3, except that it shows a different 85 form of interior spring tubing.

In the buffer shown in Figures 1, 2 and 3 there are employed two spring tubes 10 and 11, the latter being within the former, and each being preferably, but not necessarily, 90 of the same diameter, both of which are covered by the soft downy kapok, or other filling material 12, which in turn is covered and held to the interior tubes by the chamois covering 13 and the kid covering 14, which 95 are used respectively for cleaning and polishing the finger nails. It will, of course, be understood that the covering of the buffer may be entirely chamois, or entirely of kid, or entirely of some other material if so desired. 100

The tube 10, which may be made of ordinary pasteboard, cardboard, or fibre, of the desired thickness and firmness, or which may be made of thin springy metal, or other desirable material, is provided with a longitudinal slit 15, which extends from end to end of the spring tube 10. The slit 15 is preferably cut on the bias, providing the faces 16 and 17. This slit may be formed by cutting 110

out and extracting a long narrow part of a cylindrical pasteboard tube, such as an ordinary mailing tube, or a portion of a metallic tube. The purpose of forming the tube 10 with the longitudinal slit is to furnish springiness to the remainder of the tube, so that when the buffer is held in the hand of the user there is a resultant springiness in addition to the natural springiness or resiliency offered by the kapok, or other filler material. It will, of course, be understood that the longitudinal slit may be in a straight line from end to end of the tube 10, or other form, but it has been found that very good results have been obtained by the use of the straight slit cut on the bias.

The inner tube 11, as shown in the drawings, is within the tube 10. It may be constructed of the same material as the tube 10, or it may be of different material. It may also have the same length as the tube 10, or it may be longer or shorter. Good results have been obtained in the practice of the invention by causing each of the ends of the tube 10 to extend beyond the ends of the tube 11. The inner tube 11 is slit longitudinally at 18, and preferably on the bias, although that is not essential to the operation of the device. The ends 19 and 20 of the inner tube are then arranged helically so that the end 19 is within the end 20. The inner tube 11 may then be compressed to a smaller diameter by compression of the tube 10, the end 19 passing along the inner surface of the tube 11 in one direction, and the end 20 passing along the outer surface of the tube 11 in the opposite direction. It will at once be obvious from this construction of the pair of tubes—the helically arranged one within the other—that as pressure is exerted against the outer tube 10 until the edges 16 and 17 meet, the inner tube 11 is instantly and automatically compressed to a smaller diameter, as stated above. The inner tube 11, however, fitting snugly on the interior of the outer tube 10, offers resistance to the closing of the gap in the slit 15. On the release of pressure on the tube 10 the two tubes 10 and 11 spring back into normal position.

As shown more particularly in Figure 3 of the drawings, the outer tube 10 has been arranged to have its slit 15 at the top thereof approximately midway between the stitching 21 and 22 which join the chamois covering 13 and the kid covering 14. The slit 18 of the inner tube 11 is substantially in line with the stitching 21 and 22, so that the slit 18 is approximately 90° from the slit 15. It will be understood, however, that this arrangement of the tubes, having the slit of one 90° from the slit of the other, is not essential. The tubes may be arranged in any desired manner within each other, so that the spring action of both tubes, and

the resisting action of the inner tube may always be obtained.

It will, of course, be understood that the support which is desired from the core or interior tubes, and the spring action thereof, may be secured in other ways. For instance, I have shown in Figure 4 a form of an inner tube and support 23, wherein I employ a single tube either of pasteboard, cardboard, fibre, light metal, or other suitable material, which is slit at 24, and which is helically arranged, so that there are several thicknesses of the material terminating in the end 25, which may move on the inner surface of the inner layer of the material of the tube. It will be obvious from an inspection of the drawings of the tube in Figure 4 that when the tube is compressed the inner diameter of the tube is decreased, and the interior air pocket or cushion A is also compressed, and when the tube is released, the layers will slide on each other and return to their initial and normal position. It has been found in operating the structure of Figure 4, as in operating the other structure shown, that the tube furnishes springiness to the buffer, in addition to the natural springiness furnished by the kapok filling.

In assembling the manicuring buffer of Figures 1, 2 and 3 the inner tube 11 is held in position with the inner end 19 within the end 20. The inner tube 11 is then placed within the outer tube 10 with the slits in each in proper position. The kapok 12 is then placed around the tubes, completely surrounding them and forming a soft, cylindrical cushion about the inner tubes, and also forming an enclosed air pocket or cushion A within the tubes, which is variable according to the compression of the tubes. The outer covering of the chamois 13, and the kid 14 is formed by sewing the ends with the stitching 21 and 22, and reversing the chamois and the kid, so that the ends thereof shall be on the interior, thus presenting a smooth exterior surface. The outer composite covering of the chamois and kid is then stuffed with the spring tubes, covered with the kapok, or other filler, to form the manicuring buffer of the desired length. The ends 26 and 27 of the chamois covering, and 28 and 29 of the kid covering, are brought together and tied, or otherwise secured, at 30 and 31. The extensions 26 and 28 at one end of the buffer, and the extensions 27 and 29 at the other end of the buffer are then trimmed, arranged, and decorated in such a manner that they will conceal the puckering folds and stitching at the ends, and present an artistic and decorative appearance to the buffer.

It will thus be seen that by means of the invention, among other things, the outer casting or covering is supported and kept in a uniform and smooth cylindrical shape by

the interior core or tubes, although the surface tension is relieved when the buffer is being used, because of the slit in the outer tube and the helical arrangement of the inner tube; it will also be seen that because of the spring tubing, or core, and the kapok filler, the chamois and the kid are never ruffled in the operation of the buffer, and present a smooth and even surface; it will further be seen that because of the construction of the buffer there is a natural cushion formed by the soft material used, and a variable air cushion formed in the tubes, and not only is a large area of cleaning and polishing surface supplied, but the buffer operates from any angle and is easily and readily held while being used.

Having thus described the invention, what we desire to claim and secure by Letters Patent is:

1. In a manicuring buffer, the combination of a slit tube, said tube being surrounded by padding, and an outer covering therefor.
2. In a manicuring buffer, the combination of a plurality of slit tubes, one within the other, the inner tube being helically arranged, a portion of said outer tube being cut away longitudinally along the line of its slit, so that when said outer tube is compressed to cause the opposed faces of said slit to meet, said inner tube is compressed to a smaller diameter.
3. In a manicuring buffer, the combination of an interior spring tube slit longitudinally on the bias, a portion of the material of said tube along the line of said slit being cut away, a padding surrounding said tube, and an outer covering therefor.
4. In a manicuring buffer, the combination of a slit tube, said tube being surrounded by padding, and an outer covering therefor, said outer covering consisting of part chamois and part kid.
5. In a manicuring buffer, the combination of an interior spring tube slit longitudinally on the bias, a portion of the material of said tube along the line of said slit being cut away, a padding surrounding said tube, and an outer covering therefor, said covering consisting of part chamois and part kid to furnish buffing surfaces of differing qualities.
6. In a manicuring buffer, the combination of a slit tube, said tube being surrounded by padding, an outer covering therefor, said outer covering consisting of

part chamois and part kid, the ends of the chamois and kid at one end of the buffer being trimmed to form an end ornament for said buffer.

7. In a manicuring buffer, the combination of an inner spring tube slit longitudinally on the bias, a portion of the material of said tube along the line of said slit being cut away, a helically arranged tube within said last-mentioned tube, adapted to keep said slit open, a padding surrounding said tubes, and an outer covering therefor, said outer covering being composed of material of differing qualities for cleaning and buffering purposes.

8. In a manicuring buffer, the combination of an inner spring tube slit longitudinally on the bias, a portion of the material of said tube along the line of said slit being cut away, a helically arranged tube within said last-mentioned tube, adapted to keep said slit open, a padding surrounding said tubes, and an outer covering therefor, said outer covering being composed of material of differing qualities for cleaning and buffering purposes, the ends of the materials being trimmed to form end decorations for said buffer.

9. In a manicuring buffer, a padding, and a cover for said padding, said cover being provided at one of its ends with an extension which may be formed into trimming or decoration.

10. In a manicuring buffer, the combination of a slit tube, a padding surrounding said tube and leaving an enclosed air space within said tube, which air space may be varied upon pressure of said tube.

11. In a manicuring buffer, the combination of a pair of tubes, one of which is slit and has a portion of said tube cut away along said slit, one of said tubes being movable within the other, a filler which surrounds said tubes, said tubes forming an air space or cushion within said tubes and said filler, which air space may be varied upon pressure being exerted upon said tubes.

12. In a manicuring buffer, the combination of a cylindrical padding and an outer covering therefor, said buffer having no hard, exposed substance or surfaces.

In witness whereof, we hereunto subscribe our names this 7th day of May, A. D., 1926.

ZANA R. LUCAS.
GUY E. CARPENTER.
